UNITED STATES PATENT OFFICE.

ALFRED W. BRUCE, OF NEW YORK, N. Y.

LOCOMOTIVE DRIVING BOX.

Application filed February 9, 1924. Serial No. 691,585.

To all whom it may concern:

Be it known that I, ALFRED W. BRUCE, a citizen of the United States, and a resident of New York, in the county and State of New York, have invented a certain new and useful Improvement in Locomotive Driving Boxes, of which improvement the following is a specification.

My invention relates to locomotive driving boxes, of the class or type having the usual top or crown brass, and supplemental bearings in the side walls below the crown brass, and its object is to provide improved means for securing the supplemental bearings in place. The primary object of these auxiliary brasses is to prevent any tendency of the box lifting from the journal, due to excessive pressure of short main rods on two-cylinder engines, or to the effect of main rod thrust on three-cylinder engines.

In the preferred form of my invention, the auxiliary brasses are relatively narrow strips located below the centre plane of the journal, and which can be inserted in the box after the axle is in place therein.

The improvement claimed is hereinafter fully set forth.

In the accompanying drawings: Figure 1 is a front view, half in elevation and half in vertical section, of a locomotive driving box embodying my invention; Fig. 2, a side view, half in elevation and half in vertical section, of the same; Fig. 3, a plan view, half in elevation and half in horizontal section, of the same; and, Fig. 4, a vertical transverse section through a driving box illustrating a structural modification.

In the practice of my invention, referring descriptively to the specific embodiment thereof which is herein exemplified, the driving box 1, is fitted, with a crown brass, 1^a, in the usual manner, and longitudinal grooves, 1^b, extend through the driving box, below the horizontal axial plane thereof. Supplemental bearings, 2, the inner faces of which are curved concentrically with the journal, are fitted in the upper part of said grooves. The supplemental bearings are held in place, and adjusted as they wear, by wedge bars, 6, the tops of which are upwardly and inwardly inclined, and bear against correspondingly inclined faces on the bottoms of the supplemental bearings. Adjusting

bolts, 4, pass through the wedge bars, 6, and the adjoining side walls of the driving box, the heads of said bolts bearing on the inner faces of the wedge bars, and their outer end portions being threaded and carrying nuts, 4^a, by tightening which the wedge bars are drawn in, thereby raising the supplemental bearings. The nuts, 4^a, are secured in place by wedge keys, 4^b. The usual lubricant containing cellar, 3, is supported in the driving box, beneath the journal.

In the structural modification shown in Fig. 4, the crown brass, 1^a, is reduced in width, and fits on the top of the journal only, and the supplemental bearings, 2^a, are increased in width, so as to fit both above and below the axial line of the journal. Wedge bars, 6^a, and adjusting bolts, 4^a, similar to those before described, 75 act to similarly clamp the supplemental bearings in place.

The application of side supplemental bearings is of substantial advantage, in overcoming the tendency towards lifting 80 the box from the journal, due to excessive pressure of short main rods in two-cylinder engines, or the combined effort of main rod thrust in three-cylinder engines. It, therefore becomes desirable to provide facilities 85 for effecting the insertion, removal, and adjustment of the supplemental bearings, and my invention is of substantial advantage in the particulars of simplicity, strength, accessibility from the under side of the 90 driving box, facility of adjustment, and adaptability to standard existing equipment.

I am aware that supplemental bearings, fitted in a locomotive driving box, and 95 adapted for adjustment against a crown brass, have been known prior to my invention, and do not therefore broadly claim said bearings and a wedge adjustment device therefor.

I claim as my invention and desire to secure by Letters Patent:

1. The combination of a locomotive driving box; a crown brass therein; supplemental side bearings fitted therein, out of 105 contact with the crown brass; wedge bars, having transversely inclined faces, on which said supplemental bearings rest; and transversely extending adjusting bolts, bearing 110 on the wedge bars, and acting to draw them

outwardly against the supplemental bearings and the side portions of the driving box.

2. The combination of a locomotive driving box; a crown brass therein; supplemental bearings fitted in the side walls of the driving box, out of contact with the crown brass; horizontal wedge bars, located beneath said supplemental bearings, and supporting them on transversely inclined faces; bolts passing transversely through the wedge bars; and nuts on said bolts bearing on the driving box.
3. The combination of a locomotive driving box; a crown brass therein; supplemental bearings, located in grooves in the

driving box, below its horizontal axial plane, and out of contact with the crown brass, the bottoms of said supplemental bearings being transversely inclined; wedge bars seated in the driving box grooves, beneath the supplemental bearings, and bearing against the inclined bottoms of the supplemental bearings; and means for drawing the wedge bars outwardly in the grooves of the driving box, against the inclined bottoms of the supplemental bearings. 20 25

ALFRED W. BRUCE.
